UNITED STATES PATENT OFFICE.

ERNEST P. PIERCE, OF CLEVELAND, OHIO.

DIE-CASTING MACHINE.

Application filed July 26, 1920. Serial No. 399,003.

This invention relates to improvements in die casting machines.

The objects of my invention are to construct a die casting machine in which the die carrying frame is adapted to be swung into and out of operative position with respect to the other part of the device which encloses the cylinder for the molten metal and plunger; to provide fluid actuated means for moving the die carrying frame whereby the two parts will be locked in operative position; to provide fluid actuated toggle lever mechanism upon the die carrying frame which will lock the die members in operative position; to provide fluid actuated means for operating the plunger in the cylinder of the pot; to provide an arrangement which will guard against the operation of the plunger except when the die carrying frame is in operative position; to provide a means for bracing the cylinder in position; to provide a means in the lever mechanism for the operation of the plunger whereby correction may be made for inaccuracies in alignment of the bore of the cylinder and the guide for the plunger operating means; to provide an angular arrangement of the plunger and that part of the cylinder in which it operates; to provide means whereby the piston will be at all times covered by the molten metal; to provide means for varying the operative position of the die carrying frame according to the elevation of the nozzle on the cylinder; and to provide an arrangement of all the parts which will be convenient for the operation thereof.

My invention might be embodied in other forms of structure but the preferred form will be understood from the following description and claims considered in connection with the accompanying drawings.

Fig. 1 is a front elevation of my machine with parts broken away; Fig. 2 is a plan view of my machine; Fig. 3 shows diagrammatically the two positions of the die carrying frame; Fig. 4 illustrates the four-way valve structure; Fig. 5 is a plan view of a hinge rod used on the die carrying frame for the toggle levers; Fig. 6 is a front elevation of the die carrying frame showing the toggle mechanism in open position; Fig. 7 is a similar view showing the toggle mechanism in closed position; Fig. 8 is a side elevation of the die carrying frame showing the toggle mechanism in closed position; Fig. 9 is a plan view of the toggle supporting brackets;

Fig. 10 is a vertical section through the pot and cylinder; Fig. 11 is an end elevation of the means for locking the plunger operating means; Fig. 12 is a plan view of the bracing means for the cylinder; Fig. 13 is an elevation of the same bracing means; Fig. 14 is a section on line $a-a$, Fig. 12; and Fig. 15 shows the cylinder in side elevation within the pot which is shown in cross section. 60 65

My device comprises, in a general way, a stationary frame member in which is mounted the cylinder for the molten metal, and means for operating the plunger for forcing the molten metal therefrom into the die; and a die carrying frame which is mounted upon the stationary member so as to be swung through a vertical plane into and out of operative position. Details of structure will be understood from the following description. 70 75

The lower stationary part of the device is supported upon the legs 4, that part indicated at 1, and in which is enclosed the cylinder, comprising an enclosed body, while the other part of this stationary structure is open frame work. The pot 10 for the molten metal 10' is surrounded by fire brick 7 and is supported by means of a flange 11 which engages over the flange 9 which extends inwardly from the four walls of this part of the frame. The upper end of the supporting brackets 13 of the cylinder 12 rest upon the flange of the frame and are countersunk in part, as indicated at 14, so that the heads of the screws for securing these brackets in position will not interfere with the die carrying frame when it is moved into operative position. Moreover, sufficient clearance is provided for the die carrying frame. The cylinder is so arranged that the piston is always covered by the molten metal, with the result that the danger of metal freezing and jamming the piston is avoided. An opening 15 is provided in the side wall of the cylinder so as to allow the molten metal to flow into the same. The cylinder bore is restricted toward the outlet end thereof, as clearly indicated in Fig. 1. The cylinder is of a substantial V-shape, as clearly shown in Fig. 1, and it is so constructed that the two arms thereof will make an angle of less than 90° with each other, preferably from 30° to 60° ; this angle being about 45° in the present showing, and one arm being arranged vertically. 80 85 90 95

A bushing member 16 is screwed into the

cylinder and has its upper surface curved into an outlet nozzle, as indicated at 17. The plunger 18 which reciprocates in the cylinder bore is operated by the piston rod 19 which is pivotally connected at 20 to the lever operating mechanism through the compensating means which will be later described. The means for heating the metal in the pot is indicated in a general way at 2, which might be of any suitable kind, as for instance, a gas burner, while the connection 22 provides for the escape of gases which might be formed in the space 23 between the fire brick and the pot.

The air cylinder 24 with its supply pipe 25, exhaust 26 and feed pipes 27 and 28, together with the valve operating means constitute the means for operating the lever mechanism which is connected with the plunger rod of the cylinder for the molten metal. A four-way valve is provided, as illustrated in Fig. 4, whereby when this valve is set in one position by means of handle 31, connection may be established through the air supply pipe and the pipe 27 leading to the under side of the piston of the cylinder, at which time the piston will be forced upwardly. At the same time air connection is established between pipe 28 from the top of the cylinder and the exhaust 26, so that air will be forced from the top of the cylinder out through the exhaust, thus allowing the piston to rise. Then upon turning the valve in the opposite direction the reverse operation is obtained; that is, air will be forced to the upper side of the plunger and the air below the plunger will be forced out through the exhaust. This valve is in neutral position in Fig. 2 and its operation will be understood from Fig. 4 which shows the ducts 32 and 33. Other valve arrangements might be employed instead of that here shown. A lever arm 34 is pivotally connected at 35 to the upper end of the piston rod and is pivotally connected at its upper end to the lever arm 36 which is pivotally mounted at 37 upon the bracket 38. The other end of lever 36 is pivotally connected at 39 to the link member 40 which is pivotally connected at 20 to the compensating means. The mechanism for operating the plunger is so arranged with respect to the pivot point of lever 36 that there is a sufficient balance of weight on the side toward the cylinder 24, so that its piston will remain in lowered position without air pressure. Thus the air can be shut off from this cylinder when the plunger 18 is in withdrawn position.

The bracket 38 is located away from the pot so that molten metal will not splash on the bracket and cause a jamming of the parts. This bracket is made in the form of a clevis at its upper part, as clearly indicated in Figs. 1 and 2, for convenience in

mounting the lever arm or walking beam 36. This bracket has an arm 38^a to guide the piston rod of the cylinder 24. This bracket 38 is bolted to the flange at the top of the frame and is provided with ears 42 and 42' on the two sides thereof, as indicated in Figs. 12 and 14. The upper ends of the bracing rods 43, 43' are secured within these ears by means of nuts 44, 45 and 44', 45', the lower part of rods 43, 43' being provided with lugs 46, 46' which engage in cut out portions 47, 47' in the sides of the cylinder. As will be seen in Fig. 12, the lugs 46, 46' have a wedge shape and the cut out portions have inclined bottoms, as at 48, 48', so as to allow the lugs 46, 46' to be lowered within these cut-out portions and then raised into the locking position with the broader portions of the lugs engaging in the recesses 49, 49' formed by means of shoulders 50, 50'. By first engaging these lugs in the cut-out portions of the cylinder and then clamping the nuts 44, 45, and 44', 45' against the upper and lower faces of the ears 42, 42', the cylinder can be braced in proper position and will be held against accidental displacement during the operation of the machine.

Guide members 51, 51' are secured by means of bolts 52, 52' along the face of the bracket just referred to and extend inwardly over the cut-out portion 53 which is formed in the bracket member and extend parallel with the offset portions 54, 54', as indicated in Fig. 14. In this way a guide-way is provided for the slide member 55 which has its upper end pivotally connected at 20 to the lever arm 40, while in its lower end there is provided an opening 19^a somewhat larger than the cross section of the piston rod 19 for the purpose of allowing the adjustment 105 according to any inaccuracy in the bore of the cylinder, or in case there is lack of proper alignment of the bore and the guide for the plunger operating means. By giving the piston rod 19 the necessary adjustment 110 on the slide and then clamping the nuts 56, 57 against their respective seats 58, 59, a correction can be effected without disturbing the entire operative connection between the piston rod and the lever mechanism. In 115 other words, the enlarged hole 19^a in the slide member 55 allows the piston rod to be displaced in any direction across its axis. The seat members 58, 59 are formed with concave faces to receive the corresponding 120 convex faces of the nuts 56, 57, respectively, so that a more ready seating of the nuts may be had upon adjusting the piston rod 19, as just referred to.

The shaft 60 is mounted upon adjustable bearing means which will be later described. The lever arm 61 which is fast upon the shaft 60 is actuated by means of air pressure in the cylinder 62, which cylinder might be suspended from a suitable point at proper 130

elevation above the machine by means of the swinging connection 63, which is an old arrangement in the art. The lower end of the piston rod 64 is connected to the lever 61, 5 while a piston is carried upon the upper end thereof. Cylinder 62 is provided with a four-way valve 117 and its piston is operated in the same manner as that of cylinder 24. By manipulation of handle 118 connection 10 is established between supply pipe 119 and pipe 120 which leads to the upper side of the piston, the air from the under side of the piston being forced out through pipe 121 to the exhaust 122. By manipulation 15 of handle 118 in the opposite direction, the reverse connections are established. Thus the die carrying frame can be swung into and out of operative position and can be held in operative position by means of air 20 pressure, if desired. The cylinder will be supported at a sufficiently high point to allow proper operation of the piston and the swinging of the cylinder. The lever arms 66, 66' which are fastened at one end to the 25 shaft 60 have pivotal connection at 67, 67' with the connecting links 68, 68'. These links 68, 68' are curved near their other ends, as clearly indicated in Fig. 1, and are pivotally connected at 71 and 71' to the 30 bars 69, 69'. The bars 69, 69' are bolted at 70, 70' along the lower part of the die carrying frame. The hinge projections 65, 65' in the die carrying frame have bearing in the castings 65^a, 65^b on the stationary frame. 35 Fig. 1 shows the die carrying frame in operative position with respect to the rest of the device, and it will be seen from Fig. 1 that the lever mechanism just referred to is so arranged that it will lock the die carrying 40 frame in closed position. This is made possible by the fact that the points of pivotal connection 67, 67' are swung beyond the line of pivotal connections 60, 60' and 71, 71'. In other words, the link members 68, 45 68' are swung slightly beyond dead center.

The adjustable bearing means for the shaft 60 comprises plate members 72, 72' which are duplicates in structure and only one of them will be described. The plate 50 72' is pivoted to the side of the frame at 73 and is provided with means for being locked in proper position. Enlarged bolt holes are provided in the plate 72 as indicated at 74 and 75 so that this plate member can be 55 moved even though the bolts 76 and 77 pass through these openings and through the wall of the frame. When the plate member 72 has been adjusted to the proper position, the nuts on the outer ends of bolts 76 and 60 77 can be tightened to hold the plate in such position. The rod 78 is pivotally connected to the plate member 72' at the point 79 and extends through an ear formed on the side of the main part of the frame, as indicated 65 at 80. The lower end of this rod is screw-

threaded and is adapted to receive a nut 81 which can be tightened against the lower face of the ear 80 and in this way clamp the plate 72 in proper position against upward movement. A means for clamping the plate 72 in proper position against downward movement comprises a screw bolt 82 whose head supports the lower edge of the plate member 72. This screw bolt 82 carries a nut 83 which can be screwed into locking engagement against the upper face of the ear 80 into which the screw bolt 82 is adapted to be threaded. Thus it will be seen that the screw bolt 82 can be raised or lowered by being screwed up or down in ear 80 and will thus raise or lower the plate 72 since this plate member rests upon the head of this screw bolt 82. Then when the proper position is obtained the bolts 76 and 77 will be clamped and the nut 83 will be screwed tight against the ear 80. By raising or lowering the shaft 60 in this manner the length of throw of the lever mechanism is varied and adjustment is effected between the nozzle 17 on the cylinder and the lower die member. 90

A latch member is pivoted at 84 upon a bracket arm 85 which extends from the main frame of the machine, and is normally held by means of spring 86 in such position that it will lock the arm 87 of the valve operating handle 31, the pin 84^a extending from this latch member dropping into a hole 87^a in arm 87, as indicated in Fig. 11. Thus the spring 86 through the latch member normally holds the valve handle 31 in locked position so that the piston of the cylinder 24 cannot be operated when in such position. The end portion 88 of the lever arm 61 is adapted to be lowered upon the rear end of the latch member and to release the same against the tension of the spring 86; at which time the valve handle 31 can be operated for the purpose of forcing the molten metal into the die. 105

The lower and upper parts of the die are carried by the plate members 89 and 90, respectively, which are supported upon the uprights 91 forming part of the die carrying frame. The lower member 89 has fixed position upon the die carrying frame, while the upper member 90 is adapted to be moved back and forth thereupon. The lower die member is detachably mounted in plate 89 and is provided with a mouth at the lower end of its metal-receiving port to fit the nozzle 17, as will be obvious to one who is familiar with the art. Bushing members 92 are secured to the lower face of the upper member 90. Suitable openings are provided in the die to allow escape of air upon filling the die with molten metal, which is an old practice in the art and is therefore not illustrated. A fluid cylinder 93 is secured by means of bolts upon the upper face of the 115 120 125 130

die plate 90, and through the operation of the valve mechanism which controls the fluid this cylinder and die plate 90 can be moved back and forth upon the frame so as to close or open the die. The piston rod 94 is provided with ears at its upper end, which ears have pivotal connection at 95, 95' with link members 96, 96'. These link members in turn are pivotally connected at 97 and 97' with the shorter arms of the lever members 98, 98', the last named levers being pivotally mounted upon bearings 99, 99' which will be later referred to in detail. Levers 98, 98' are of an open frame structure and are narrowed from the upper to the lower end so as to swing between the bearings 99, 99'. These two levers are duplicates. The other end of the lever 98 is pivotally connected at 100 to the lever arms 101, which last named lever arms are pivotally connected at 102, to the hinge rod 103 mounted on the main supporting bars 104. The bars 104 are held in fixed position by means of nuts 105 engaging the screw threads on the uprights, as shown, and hinge rods 103 are curved at the middle portions 106, as seen in Fig. 5, to accommodate the upper end of the cylinder as it moves past these rods. These supporting bars are duplicates; and likewise the two hinge rods. The last named bars 104 remain in fixed position during the reciprocatory movement of the piston and cylinder, with the result that when fluid is forced upon the upper side of the piston, the lever members will be moved from the position shown in Fig. 6 to that shown in Fig. 7. The piston under the force of the fluid pressure folds the lever arms in the manner just referred to and will also carry the cylinder with the upper die plate to the position illustrated in Fig. 7. Thus it will be seen that the die is closed with a positive force and an effectual lock is obtained by straightening the toggle lever mechanism to prevent accidental opening of the die.

Cylinder head 106 is secured by bolts to the cylinder as shown and upon the cylinder head there are provided two bracket members having semi-circular feet 107, 107' secured by means of bolts as shown. The legs 109, 109' are provided at their upper ends with bearings 99, 99' for the lever arms 98, 98'. As clearly shown in Fig. 9, sufficient space is allowed between the guide bearings 110, 110' and 99, 99' to accommodate the lever arms 101, 101'. As will be seen from the drawings the legs 109, 109' extend upwardly and outwardly from the semi-circular feet and there are web connections between the webs 111, 111', which connect the guide bearings 110, 110', and the feet 107, 107', as well as between the web portions 111, 111' and the bearings 99, 99'. These two bracket members are of like structure. The feet of the bracket members just referred to are given sufficient inside curvature to allow free access to the stuffing box of the piston. Sufficient space is also provided between the legs of the brackets to allow folding of the links 96, 96', as seen in Figs. 6, 7 and 9.

A four-way valve 112 like that described before and illustrated in Fig. 4, is employed in connection with the operation of cylinder 93, that is to say, when the valve 112 is set in one position, air connection is obtained through the supply pipe 113 and the pipe 114 which has connection with the upper side of the piston. At the same time the pipe 115 from the lower face of the piston is connected with the exhaust 116. Then upon setting the valve 112 in the other position, the supply pipe 113 is connected through pipe 115 with the under side of the piston and the pipe 114 is connected with the exhaust. The upper die plate 90 is bored out as indicated in dotted lines at 90^a for passage of air to the lower end of the cylinder, that is, from pipe 115 to the under side of the piston. The flexible pipes or tubes 113, 114 and 115 are connected as shown in Fig. 1 with the metal pipes of the valve and cylinder. Other valve arrangements might be used at this point instead of that shown.

The parts on the die carrying frame, including the cylinder, its piston and piston rod, are of sufficient weight to hold the die in closed position without maintaining the air compression, even though the toggle levers are not brought to fully straightened position.

The operation of this device briefly stated is as follows:

First, the upper part of the die is closed upon the other part of the die and locked in such position as explained; and then the die carrying frame is swung from horizontal to vertical position so as to bring the die in co-operative relation with respect to the nozzle upon the cylinder. This is accomplished by means of the air cylinder 62. The air upon being admitted to the under face of the piston will force rod 64 upwardly and will cause swinging movement of the lever arm to the right, the air above the piston being exhausted at the same time through the pipe 120. Then when the lever arm 61 reaches the crest in its rotary motion it will move downwardly to the right so as to assume the position shown in Fig. 1. As soon as the crest is reached the operator will manipulate the valve so as to gradually admit air through pipe 120 to the upper side of the piston so as to gradually release the air from the under side of the piston, thus allowing the die carrying frame to lower to its normal position against the air compression on the under side of the piston. This will prevent any sudden jarring of the die carrying frame as it moves into position over the pot. The

curved portion of the link members 68, 68' will then come to rest upon the shaft 60, sufficient clearance being provided between the bearings and the lever connections. When 5 the lever arm 61 has come to its full lowered position, thereby locking the die carrying frame as explained, the end of lever 61 will depress the latch member against the tension of spring 86 and will thus allow the operation 10 of the valve handle 31. The operator can then turn air onto the lower face of the piston in cylinder 24 and in this way force the metal from the pot into the die. Then having filled the die by operation of the 15 valve, the die carrying frame will be swung to the left by turning the valve to admit air to the under side of the piston and to connect pipe 120 with the exhaust. As soon as the lever arm 61 reaches its crest in its 20 rotary movement to the left, the operator will gradually reverse the air connections so as to release the air from the under side of the piston, and in this way accomplish a gradual lowering of the die carrying frame 25 to its horizontal position, using the air compression under the piston to prevent any sudden jarring thereof. The casting can then be removed from the die and the same operation repeated.

30 With my arrangement all of the parts are conveniently and compactly located with respect to each other and decided advantages are realized in the operation of the piston for forcing the molten metal into the die, and 35 also in connection with the operation for closing the die members. Among other advantages resulting from my device is that which resides in the particular arrangement of the cylinder. As will be seen from Fig. 40 1, that portion of the cylinder which has the enlarged part of the bore makes an angle of approximately 45° with respect to its other part. As the result of this arrangement the piston operates at an angle substantially 45° to the horizontal, and by 45 means of the particular lever connections the air cylinder for operating the same is conveniently located on one end of the machine. Then, too, by having the piston always covered with the molten metal there is no danger of such metal freezing or causing the piston to jam in the cylinder. The advantages resulting from the lever operating means which allows the locking of the die carrying frame in operative position, as well 55 as that resulting from the means for preventing actuation of the plunger before the die carrying frame is in operative position will be obvious; as also that resulting from 60 the means for bringing the die members together and securing them in closed position. The adjustable bearing for the shaft which is connected with the levers for moving the die carrying frame constitutes another advantage 65 in connection with the proper seat-

ing of the die carrying frame upon the nozzle. With this arrangement it is possible to properly position the die carrying frame with respect to different cylinders in which the nozzles terminate at different elevations. 70 Further advantages are found in the means for bracing the cylinder against accidental displacement, and also in the means for compensating for any inaccuracies in the bore of the cylinder or in the alignment of the 75 bore and the guide for the lever mechanism. A still further advantage resides in the fact that it is not necessary to maintain air pressure in the cylinder 24 in order to hold the plunger withdrawn from the cylinder for 80 the molten metal.

The upper movable support for the toggle levers and the upper die plate constitute a double guide for the parts which are moved along the die carrying frame. And by arranging the fixed supports for the toggle levers between the upper toggle supports which are movable and the upper die plate which is also movable, the weight of the 85 parts upon the frame is to a large extent kept low. Furthermore, the arrangement of the cylinder between the movable members just referred to produces a more efficient operation of the parts along the frame. Still another advantage resides in the fact that 90 the die can be maintained in closed position by the air pressure or the air can be cut off, the die remaining closed under the weight of the parts, even though the toggle levers are not in fully straightened position. 95

Other advantages resulting from this particular device will readily suggest themselves to those who are familiar with the art to which it relates.

What I claim is:

1. In a die casting machine, the combination of a frame, a cylinder in said frame, a plunger mounted on said frame at an angle of substantially 45° to the vertical, means for operating said plunger in said cylinder, and a swingingly mounted die carrying frame adapted to be swung into and out of vertical position above the cylinder. 105
2. In a die casting machine, the combination of a frame, a cylinder stationary in said frame, a plunger for said cylinder, means for operating said plunger, a swingingly mounted die carrying frame and fluid compression means for swinging said frame into and out of vertical position above the cylinder and for producing opening and closing movement of the upper die on said die carrying frame. 115
3. In a die casting machine, the combination of a frame, a cylinder in said frame, a plunger for said cylinder, means for operating said plunger, a swingingly mounted die carrying frame adapted to be swung into and out of operative position, lever mechanism for effecting such swinging movement, 125

said lever mechanism adapted to be swung beyond dead center so as to lock said die carrying frame in operative position.

4. In a die casting machine, the combination of a frame, a cylinder in said frame, a plunger for said cylinder, means for operating said plunger, a swingingly mounted die carrying frame adapted to be swung into and out of operative position, levers connecting said frames and adapted to be swung past dead center to lock the die carrying frame in closed position, and means for effecting such swinging movement of the die carrying frame.

5. In a die casting machine, the combination of a frame, a cylinder in said frame, a plunger for said cylinder, means for operating said plunger, a swingingly mounted die carrying frame adapted to be swung into and out of operative position, lever arms connected to the stationary and die carrying frames and having pivotal connection with each other, said lever arms being so constructed and arranged that the point of pivotal connection between said lever arms may pass beyond dead center upon operation of said lever arms for bringing the die carrying frame to operative position.

6. In a die casting machine, the combination of a frame, a pot supported in said frame, a cylinder in said pot, and having a bore of angular extent, the discharge portion of said angular bore being substantially vertical, a plunger for operation in the bore of said cylinder, and means for operating said plunger, the parts being so arranged that the plunger bears an acute angle to the horizontal.

7. In a die casting machine, the combination of a frame, a pot supported in said frame, a cylinder in said pot having a plunger bore at an angle to the vertical, a bracket upon said frame, and bracing rods having connection with said cylinder and said bracket and extending at an angle corresponding to the angle of the plunger bore.

8. In a die casting machine, the combination of a frame, a pot supported in said frame, a cylinder in said pot, a plunger for operation in said cylinder, means for operating said plunger and an adjustable connection between said operating means and the plunger allowing adjustment thereof.

9. In a die casting machine, the combination of a frame, a pot supported in said frame, a cylinder in said pot, a plunger for operation in said cylinder, means for operating said plunger, said operating means including a connection allowing adjustment in a plane transverse to the direction of operation of said plunger.

10. In a die casting machine, the combination of a frame, a pot supported in said frame, a cylinder in said pot, a plunger for co-operation with said cylinder, a bracket

upon said frame, means for operating said plunger including a member having sliding relation with said bracket, said member having adjustable connection with said operating means.

11. In a die casting machine, the combination of a frame, a cylinder in said frame, a plunger for said cylinder, means for operating said plunger, control means for said operating means a die carrying frame adapted to be moved into and out of operative position, means for controlling the die carrying frame in its movements and means under control of the die carrying frame for locking the control means of said plunger operating means in inoperative position.

12. In a die casting machine, the combination of a frame, a cylinder in said frame, a plunger for said cylinder, means for operating said plunger, a die carrying frame adapted to be moved into and out of operative position, means for locking said operating means in inoperative position, and means under control of said die carrying frame for releasing said locking means.

13. In a die casting machine, the combination of a frame, a cylinder in said frame, a plunger for said cylinder, means for operating said plunger, a die carrying frame adapted to be moved into and out of operative position, and means for moving said die carrying frame into and out of operative position, the plunger operating means being under control of said last named means and separate control means for the plunger and die carrying frame operating means.

14. In a die casting machine, the combination of a frame, a cylinder in said frame, a plunger for said cylinder, a die carrying frame adapted to be moved into and out of operative position; valve-controlled fluid means for operating the plunger, and means under control of the die carrying frame for locking and releasing said valve control of the fluid operating means for said plunger.

15. In a die casting machine, the combination of a stationary frame, a cylinder in said frame, a swingingly mounted die carrying frame, means for swinging said die carrying frame into and out of operative position, said means including an adjustable pivotal bearing, whereby the position of the die carrying frame with respect to the cylinder can be varied.

16. In a die casting machine, the combination of a stationary frame, a cylinder in said frame, a die carrying frame operatively associated with said cylinder and being provided with relatively movable die supporting plates, and means for bringing said die supporting plates into and out of closed relation, said means including double toggle lever mechanism, said toggle lever mechanism being so constructed and arranged that when the die supporting plates are in closed

position the toggle levers are in collapsed and approximately straightened position, thereby providing a lock for said die supporting plates.

5 17. In a die casting machine, the combination of a stationary frame, a cylinder in said frame, a swingingly mounted die carrying frame, lever mechanism for swinging said die carrying frame into and out of operative position, and means for varying the position of the fulcrum of said lever mechanism to thereby vary the length of throw of the same, whereby the position of the die carrying frame with respect to the cylinder 10 can be varied.

15 18. In a die casting machine, the combination of a stationary frame, a cylinder in said frame, a swingingly mounted die carrying frame, means for swinging said die carrying frame into and out of operative position, and means for varying the swinging connection between the die carrying frame and the means for swinging the same, whereby the position of the die carrying 20 frame with respect to the cylinder can be varied.

25 19. In a die casting machine, the combination of a stationary frame, a cylinder in said frame, a swingingly mounted die carrying frame, means for swinging said die carrying frame into and out of operative position, said means including a bearing member for said swinging means, said bearing member being pivoted to said frame and having 30 means for securing the same in adjusted position.

35 20. In a die casting machine, the combination of a stationary frame, a cylinder in said frame, a swingingly mounted die carrying frame, means for swinging said die carrying frame into and out of operative position, said means including a bearing member for said swinging means, said bearing member being adjustable upon said frame and 40 means for securing the same in adjusted position.

45 21. In a die casting machine, the combination of a stationary frame, a cylinder in said frame, a swingingly mounted die carrying frame, means for swinging said die carrying frame into and out of operative position, said means including a bearing member for said swinging means, said bearing member being adjustable upon said frame in a 50 vertical plane, and means for locking said bearing member against upward and downward movement.

55 22. In a die casting machine, the combination of a stationary frame, a cylinder in said frame, a swingingly mounted die carrying frame, means for swinging said die carrying frame into and out of operative position, said means including a plurality of bearing members for said swinging 60 means, said members being adjustably 65

mounted and means for securing the same in adjusted position.

23. In a die casting machine, the combination of a stationary frame, a cylinder in said frame, a swingingly mounted die carrying frame, means for swinging said die carrying frame into and out of operative position, said means including a plurality of independently adjustable bearing members for said swinging means. 75

24. In a die casting machine, the combination of a stationary frame, a cylinder in said frame, a swingingly mounted die carrying frame, means for swinging said die carrying frame into and out of operative position, said means including a plurality of bearing members for said swinging means, said members being capable of independent adjustment and means for securing the same in adjusted position. 80

25. In a die casting machine, the combination of a frame, a pot supported in said frame, a cylinder in said pot, a plunger for operation in said cylinder, and lever mechanism for operating said plunger, said lever mechanism being so constructed and arranged that the weight of the power end thereof will of itself maintain said plunger in withdrawn position. 85

26. In a die casting machine, the combination of a frame, a pot supported in said frame, a cylinder in said pot, a plunger for operation in said cylinder, fluid actuated lever mechanism for operating said plunger, the weight of said mechanism being so distributed with respect to the fulcrum point that the power end thereof will be maintained in withdrawn position by gravity alone. 90

27. In a die casting machine, the combination of a frame, a cylinder in said frame, a plunger for said cylinder, means for operating said plunger, a swingingly mounted die carrying frame adapted to be swung into and out of operative position, lever arms connected to the stationary and die carrying frames and having pivotal connection with each other, said lever arms being so constructed and arranged as to effect swinging of the die carrying frame into and out of operative position. 105

28. In a die casting machine, the combination of a frame, a cylinder in said frame, a plunger for said cylinder, means for operating said plunger, a die carrying frame adapted to be moved into and out of operative position, and fluid compression means for opening and closing the die, said means including a cylinder mounted for movement in a path in substantial alignment with that of the dies in closing and opening. 110

29. In a die casting machine, the combination of a stationary frame, a cylinder in said frame, a die carrying frame operatively associated with said cylinder and be- 115 120 125 130

ing provided with relatively movable die supporting plates, and fluid compression means for bringing said die supporting plates into and out of closed relation, said means including a cylinder mounted upon the outer face of one of said die plates.

30. In a die casting machine, the combination of a stationary frame, a cylinder in said frame, a die carrying frame operatively associated with said cylinder and being provided with relatively movable die supporting plates, and means for bringing said die supporting plates into and out of closed relation, said means including mechanism movably mounted upon said die carrying frame and having guide connections at a plurality of points along said die carrying frame.

31. In a die casting machine, the combination of a stationary frame, a cylinder in said frame, a die carrying frame operatively associated with said cylinder and being provided with relatively movable die supporting plates, and means for bringing said die supporting plates into and out of closed relation, said means including fluid actuated mechanism, said mechanism having spaced connections with said die carrying frame for movement therealong, and a fluid cyl-

inder forming a part of said mechanism located between said spaced connections.

32. In a die casting machine, the combination of a stationary frame, a cylinder in said frame, a die carrying frame operatively associated with said cylinder and being provided with relatively movable die supporting plates, and means for bringing said die supporting plates into and out of closed relation, said means including a mechanism having spaced connections with said die carrying frame for movement therealong, and having also a fixed connection with said die carrying frame at a point between said spaced connections.

33. In a die casting machine, the combination of a stationary frame, a cylinder in said frame, a die carrying frame operatively associated with said cylinder and being provided with relatively movable die supporting plates, and means for bringing said die supporting plates into and out of closed relation, said means including mechanism so constructed and arranged that said die members can be maintained in closed position by the weight of said mechanism alone.

In testimony whereof I affix my signature.

ERNEST P. PIERCE.
